UNITED STATES PATENT OFFICE

166,936

COFFEE POT

Franz Wagner, Chicago, Ill., assignor to
Easterling China Company

Application October 30, 1951, Serial No. 17,171

Term of patent 3½ years
(Cl. D44—26)

To all whom it may concern:

Be it known that I, Franz Wagner, a citizen of the United States, residing at Chicago, county of Cook and State of Illinois, have invented a new, original, and ornamental Design for a Coffee Pot, of which the following is a specification, reference being had to the accompanying drawing, forming a part hereof.

Fig. 1 is a perspective view of a coffee pot showing my new design;

Fig. 2 is a plan view thereof;

Fig. 3 is a side elevational view thereof;

Fig. 4 is a front elevational view thereof;

Fig. 5 is a back elevational view thereof;

6—6 of Figure 3; and

I claim:

The ornamental design for a coffee pot, as shown.

FRANZ WAGNER.
